United States Patent Office.

DESIGN FOR A KNIFE HANDLE.

HENRY H. HAYDEN, OF NEW YORK, N. Y., ASSIGNOR TO HOLMES, BOOTH,
& HAYDEN, OF WATERBURY, CONNECTICUT.

Design No. 2,530, dated December 18, 1866.

The Schedule referred to in these Letters Patent and making part of the same.

TO ALL WHOM IT MAY CONCERN:

Be it known that I, HENRY H. HAYDEN, of the city and State of New York, have invented or produced a new and original Design for the Handles of Knives; and I do hereby declare the following to be a correct description of the same, reference being had to the annexed photograph, showing the said handle in perspective.

The general shape of said handle is prismatic, its upper and lower sides being nearly flat at the part *a*. The outline of the handle, horizontally, is curved, and the edges bevelled. At the end and near the centre of the handle are beaded ovals, surrounded with scrolls and leaves, as at *b* and *c*. The bevelled edges are ornamented with corrugated and circular-ended beads, as at *d*, and the end portion of the handle towards the knife is ornamented with longitudinal and semicircular-ended beads, at *e*.

What I claim, and desire to secure by Letters Patent, is—

The design for a knife handle, as described and shown.

In witness whereof I have hereunto set my signature this fifteenth day of November, A. D. 1866.

H. H. HAYDEN.
